UNITED STATES PATENT OFFICE.

RUDOLPH WEHR, OF NEW YORK, N. Y.

ROTARY VALVE.

1,347,978.

Specification of Letters Patent. Patented July 27, 1920.

Application filed May 2, 1919. Serial No. 294,232.

To all whom it may concern:

Be it known that I, RUDOLPH WEHR, a citizen of Hungary, and a resident of New York city, in the county of New York and State of New York, have invented certain new and useful Improvements in Rotary Valves, of which the following is a specification.

This invention relates to rotary valves and more particularly to a type adapted for use in internal combustion engines for controlling the admission or escape, or both, of the gases to or from the cylinder. The valves of this type ordinarily have a peripheral portion exposed to the gas pressure within the cylinder at the time of the explosion and while the valve is rotating. Much trouble is caused by the wear of the valves, particularly when this wear has increased to such an extent that the gas at the time of compression or explosion may escape between the valve and its casing.

In my improved construction, I provide an adjustable member which presents one surface following the cylindrical surface of the valve and an outer surface curved about a different center laterally disposed in respect to the axis of the valve. This member although following the contour of the valve, in effect, constitutes a curved wedge of materially greater thickness at one point than at another so that when it is adjusted circumferentially of the valve, the resulting inward or radial movement of the inner surface toward the valve will be comparatively slight but will be following said surface and very accurate adjustment may be secured. It is essential that the wedge be so mounted in respect to the direction of rotation of the valve that the friction of the latter tends to move the wedge toward its base or thicker end and give increased play to the valve when the latter expands with heat or the lubrication proves inefficient. Means are provided which automatically tend to move the wedge toward its edge or thinner portion so as to maintain a proper fit at all times.

Although my improved construction is particularly adapted for the intake valve, the exhaust valve, or the combined intake and exhaust valve of an internal combustion engine, yet it will be apparent that it may be used in connection with any rotary valve of substantially cylindrical form where there is liability of material wear which is

to be taken up and where a particularly tight fit is to be maintained.

In the accompanying drawings to which reference is to be had I have illustrated two embodiments of my invention, although it will be understood that I do not wish to be limited to the specific construction there shown except as defined in the appended claims.

In these drawings:

Figure 1 is a section through the cylinder head of an engine at right angles to the axis of the valve.

Fig. 2 is a central longitudinal section, the valve being omitted, and,

Fig. 3 is a section similar to Fig. 1 but omitting the valve and showing a modified adjusting means.

In the drawings I have shown a cylinder 10 having a cylinder head 11 which operates with a casting 12 to form a casing for a rotary valve 13. In the specific form illustrated, the upper casting or valve casting block 12 has an inlet port 14 and an exhaust port 15 while the cylinder head has a port 16 communicating with the valve. The valve is of such form that when in one position it connects the port 16 with the inlet port 14 while in another position it connects the port 16 with the exhaust port 15. The valve is intended to rotate continuously and uniformly at a speed equal to one fourth the crank shaft speed. The particular valve shown constitutes no portion of my present invention but it is essential that it rotate in such a direction that the surface engaging the wedge always moves toward the base of the wedge.

As an important feature of my invention I provide the valve casing with an adjustable lining member 17. This has a substantially semi-cylindrical inner surface 18 fitting the peripheral surface of the valve along approximately one half the circumference of the latter and provided with a port 19 which registers with the port 16. In other words, the member 17 is on the side of the valve toward the cylinder although this is not essential under some circumstances. The lower valve casing member or cylinder head 11 has a substantially semi-cylindrical socket 20 therein, which corresponds to the external surface of the member 18 although its axis is laterally offset in respect to the axis of the valve. In other words, the internal surface of the member 17 is concentric with the

valve while the external surface is eccentric, whereby the member 17 is materially thicker at one edge than at the other and in effect constitutes a curved wedge.

Opposite to the adjustable valve casing lining member 17 I preferably provide a second valve casing lining member 22 which is rigidly secured within the upper valve casting section 12. This may have its outer and inner surfaces concentric and may be held in position in a suitable manner, as for instance, by one or more screw bolts 23 with their heads countersunk as shown.

Between the ends of the two lining members 17 and 22 there is left a narrow gap or slot 24 on the narrow end of the curved wedge so that as the valve and lining members wear, the lining member 17 may be adjusted circumferentially and inwardly to take up for the wear. Any suitable means may be employed for automatically bringing about the desired adjustment. As shown in Fig. 3, I employ an operating rod 25 slideable in the lower valve casing member 11 and having one end seating in a socket 26 in the periphery of the member 17. The general direction of the rod 25 is substantially tangential to the valve so that by moving the rod endwise, the member 17 is shifted circumferentially. As shown, a coil spring 27 encircles the outer end portion of the rod 25 and abuts against a shoulder 28 on the rod and an outer cap 29, threaded on a boss 30. The spring constantly tends to push the rod inwardly and move the wedge to its innermost position permitted by wear. By turning the cap 29, the tension of the spring may be increased or decreased at will. In Fig. 1, I have shown a rod 31 disposed substantially radially of the valve and having a wedge end 32 acting against a wedge surface at the thicker end of the member 17. The inward radial movement of the rod 31 causes a circumferential movement of the member 17. At the outer end of this rod, I have shown the same automatic adjusting means as I have shown in connection with the rod 25.

For a single cylinder engine any suitable means may be employed for closing the ends of the slot or gap 24 to prevent the escape of any gas lengthwise of the valve. For a multiple cylinder engine I may use one valve extending along the entire row of cylinders but preferably make the member 17 of sections, one section for each cylinder, so that they may be independently adjusted to compensate for unevenness or irregularity in wear. The member 17 may have peripheral flanges at its extremities or peripheral extensions 33 at the ends of its side edges entering corresponding sockets 34 in the opposed edges of the valve casing lining 12. The sockets may be sufficiently deep to permit of the circumferential adjustment of

the member 17 but fit so as to prevent any longitudinal movement of the member 17 or any longitudinal flow of gas along the slot or groove 24.

By means of my improved construction, any wear in the lining member 22 is taken up by the corresponding slight upward movement of the rotary valve, and this upward movement as well as the wear on the inner surface of the member 17 is compensated for by the circumferential movement of the member 17 and as the latter presents a cylindrical surface following substantially one half the periphery of the valve, a tight and effective seal is maintained at all times and the escape of gas during the compression and explosion strokes of the piston is prevented even though the valve materially wears.

The valve rotates in such a direction (counter-clockwise as shown in the drawings) as to constantly tend to move the wedge member toward its base or upper end and by having the wedge member held in place by a spring action, any freezing of the valve in case of failure of the lubricating system is prevented. Any binding of the valve will automatically move the member 17 back and increase the available space for the valve and thus prevent any binding action.

Although I have shown the member 22 stationary, and rigidly secured in place, but the construction and even the presence of this member is not an essential to my invention.

I have not illustrated any means for lubricating the valve nor have I attempted to accurately show the proper sizes and positions of the ports. It will of course be understood that suitable lubricating means will be provided and that the ports will be so positioned and of such size as to accomplish the desired functions for the successive piston strokes of the engine cycle whether the latter be two stroke cycle or four stroke cycle.

Having thus described my invention what I claim as new and desire to secure by Letters Patent is:

1. In an engine the combination of a rotary valve having normal rotation in one direction only and a valve casing including a curved wedged member presenting an inner cylindric surface following the contour of the valve and an outer cylindric surface eccentric to the valve axis and means for insuring a proper running fit during varying operating conditions including means yieldingly resisting but permitting limited movement of said wedge member circumferentially of the valve toward the larger or base edge of the wedge by the frictional engagement of said valve with said wedge member during the rotation of said valve.

2. In an internal combustion engine of the rotary valve type, a valve casing including a substantially semi-cylindrical lining member, said member having its inner surface 5 concentric with the valve and its external surface eccentric whereby one edge of said member is materially thicker than the opposite edge, a rotary valve engaging with said member and having a normal rotation with 10 its surface engaging with said lining member tending to move the latter toward its thicker or base edge to increase clearance, and resilient means normally tending to move said lining member toward its narrow 15 edge to decrease clearance.
3. In combination a rotary valve having normal rotation in one direction only, a

valve casing including a substantially semi-cylindrical stationary member and a substantially semi-cylindrical movable member 20 of greater thickness at one edge than at the opposite edge, the frictional engagement of said valve with said second mentioned member normally tending to move the latter circumferentially of the valve a limited distance to thereby increase clearance of the valve and a spring coöperating with said second mentioned member normally tending to resist said movement.

Signed at New York, in the county of 30 New York and State of New York, this 23rd day of April, A. D. 1919.

RUDOLPH WEHR.
